UNITED STATES PATENT OFFICE.

FRIEDRICK KITZLER, OF ELIZABETH, NEW JERSEY.

ATTACHMENT FOR GAS-COCKS.

SPECIFICATION forming part of Letters Patent No. 548,370, dated October 22, 1895.

Application filed November 21, 1894. Serial No. 529,480. (No model.)

To all whom it may concern:

Be it known that I, FRIEDRICK KITZLER, a citizen of the United States, residing at Elizabeth, in the county of Union and State of New Jersey, have invented a certain new and useful Improvement in Attachments for Gas-Cocks, fully described and represented in the following specification and the accompanying drawings, forming a part of the same.

This invention relates to a novel means of preventing the accidental reopening of the gas-cock after closing the same to shut off the gas-supply and extinguish the light, in order to avoid waste of gas and the injurious effects of such escaping gas upon the occupants of the apartment which would result from such inadvertance.

The invention consists in the particular construction for such an attachment as herein shown and described.

In the annexed drawings, Figure 1 is an elevation of my attachment applied to the plug of a gas-cock, with the remainder of the fixture indicated in dotted lines. Fig. 2 is a plan of the attachment and the plug, and Fig. 3 is an end view of the clamping-ring and the block pivoted thereto. Fig. 4 is an elevation similar to Fig. 1, showing the catch formed as a leaf-spring. Fig. 5 is a plan and Fig. 6 an end view of the catch-lever.

The fitting *a* is shown provided with the burner *b* and with the plug *c*, having the key or thumb-piece *d* for turning the same, and the stop-pin *d'* to engage stop-shoulders *e* upon the fitting in the usual manner.

To the outer end of the socket *a'* is applied a band *f*, having lugs *f'* at the ends, which are drawn together by the screw *g* to form a clamp-ring for securing the attachment in place. Upon the outer edge of this band are provided the lugs *f''*, bent into hooks conforming with and embracing the outer flange of the fitting to prevent the lateral displacement of the clamp-ring *f*. The lower side of the ring is formed with perforated ears *f''*, to which is pivoted the flat block *h*, clamped to the catch-lever *l* by means of a screw *i*, inserted in the slot *j*. The catch-lever, which is shown herein formed of sheet metal, terminates at the end adjacent to the plug *c* in a yoke *l'*, embracing the same, having its extremities turned downward to offer a substantial bear-

ing-surface for the stop-pin *d'*, and is formed at the opposite end with a projecting portion *l''*, forming a handle for actuating the same. 55 A spring *r* is interposed between the block *h* and the ring *f* and operates to press the yoke normally upward into the path of the stop-pin.

It will be observed that when the gas is turned off and the key *d* and stop-pin *d'* assume the positions shown in full lines in Fig. 1 the stop-pin is positively confined between the stop-shoulder *e* and the ends of the yoke *l'* until the yoke is depressed by elevating the handle *l''*, when the plug becomes free to turn, 60 as indicated in dotted lines in the said figure. The release of the lever permits the yoke to rest against the under side of the stop-pin by the actuation of the spring until the cock is again closed, when the pin is rotated out of 65 engagement with the yoke and the latter assumes its normal position in the path of the pin, as before.

It will be observed that the attachment as above described is adapted for application to 75 fittings of different sizes and proportions by means of the slot *j* in the lever, whereby the position of the block *h* and its clamp-screw *i* may be adjusted to suit the distance of the ears *f''* from the center of the plug *c*. 80

In Figs. 4, 5, and 6 I have shown a somewhat simpler form of catch for effecting the object described above. In this form of the invention the spring catch-lever, which is formed of a leaf-spring *s*, is clamped at one end by 85 means of a screw *o* upon a suitable seat *a''* upon the fitting, which may be cast integral therewith or soldered thereon; or the flange may be filed flat to receive such spring-lever. The free end of the lever is provided with a 90 yoke *s'*, similar to that of the lever *l*, above described, having radial notches *s''* in its upper side of any desired number and spacing to engage the pin in its different positions. The degree of abruptness of these notches 95 and their depth will determine their manner of engagement with the stop-pin, whether their action shall be positive or shall offer merely a yielding barrier to the motion of the plug. A thumb-piece *s''* is provided at one or both sides of the spring-catch for convenience in shifting the yoke out of the path of the stop-pin.

It is obvious that for cocks having the stop-

shoulders at right angles to each other only one of the arms of the yoke would be necessary, as the plug would be turned in the same direction at all times to close the cock, and 5 that the stop-shoulders may be readily dispensed with by suitably varying the form of the operative end of the lever.

It will be observed from the foregoing description that the details of construction of 10 the device are wholly immaterial to the essential feature of the invention, which is the spring-lever having a yoke embracing the plug and lying normally in the path of the stop-pin.

15 In the following claims I have made reference to the "inner face" of the spring-lever, by which is to be understood the face of the same presented to the cock and nearest thereto.

20 I am aware that it has been proposed heretofore to form peripheral notches in the washer upon the smaller end of the plug of a gas-cock for engagement with the outer ends of a pair of spring-arms which lie and are movable 25 only in the plane of such washer, and that it is not new to project a flat spring into engagement with the key of a gas-cock, such spring being movable transverse to the center line of the key. My invention differs from such 30 constructions in comprising a spring formed with a rigid yoke embracing the plug of the cock to lock its stop-pin by contact with the extremity of an arm of the said yoke when the plug is in its normal or closed position 35 and adapted to be shifted out of the path of the pin and transverse thereto and to rest thereon when the plug is turned in any other than its normal position.

Having thus set forth the nature of the invention, what I claim herein, and desire to 40 secure by Letters Patent, is—

1. The combination, with a cock having a 45 rotary plug provided with a lateral stop pin, of a spring lever having one end secured upon the cock and the other end formed with a rigid yoke embracing the plug and lying normally in the path of the said pin with one of its extremities in engagement therewith when the plug is in its closed position to lock the 50 same from turning, and adapted to be shifted out of the plane of such path and transverse thereto to release the said pin and to rest its inner face against the said pin in all other positions of the latter, as and for the purpose 55 set forth.

2. The combination, with a cock having a 60 rotary plug provided with a lateral stop pin, of a spring lever having one end secured upon the cock and the other end formed with a rigid yoke embracing the plug with its extremities bent at right angles thereto to engage the said pin in order to lock the plug in its initial position with its stop pin transverse to the spring lever, and adapted to be shifted

transversely out of the plane of the path of 65 the said pin to release the latter and to rest with its inner face against the said pin in all other positions of the latter, as and for the purpose set forth.

3. The combination, with a cock provided 70 with a rotary plug having a stop pin, of a lever having a rigid yoke at one end embracing the said plug and adapted to engage its pin, and formed with a slot intermediate to its ends, perforated ears upon the cock, a 75 block secured adjustably to the said lever by means of a screw inserted in its slot and having an ear pivoted to the ears upon the cock, and a spring for sustaining the said lever with its yoke normally in the path of the stop pin, substantially as shown and described.

4. The combination, with a cock provided 80 with a rotary plug having a stop pin, of a clamp ring fixed thereon and provided with 85 perforated ears projected therefrom, a lever having a yoke at one end embracing the said plug and adapted to engage its stop pin, and formed with a slot intermediate to its ends, a block secured adjustably to the said lever by 90 means of a screw inserted in the said slot and having an ear pivoted to the ears upon the clamp ring, and a spring for sustaining the said lever with its yoke normally in the path of the stop pin, substantially as shown and described. 95

5. The combination, with a cock provided 100 with a rotary plug having a stop pin, of a divided clamp ring formed with outwardly projecting hooks along one edge in engagement with the outer end of the fitting and provided 105 with perforated ears as described, a lever having a yoke at one end embracing the said plug and adapted to engage its stop pin, and formed with a slot intermediate to its ends, a block secured adjustably to the said lever by 110 means of a screw inserted in the said slot and having an ear pivoted to the ears upon the clamp ring, and a spring for sustaining the said lever with its yoke normally in the path of the stop pin, substantially as herein shown 115 and described.

6. The attachment for gas-cocks comprising 120 a divided clamp ring, a lever provided at one end with a yoke adapted to embrace the plug of the cock and having a longitudinal slot intermediate to its ends, a block pivoted to the said clamp ring and secured adjustably to the lever by means of a screw inserted in its slot, and a spring interposed between the said block and the clamp ring, as and for the purpose set forth.

In testimony whereof I have hereunto set my hand in the presence of two subscribing witnesses.

FRIEDRICK KITZLER.
